TAPE DISPENSER

Edwin C. Addis, Florence, Mass., assignor to Chart-Pak, Incorporated, Leeds, Mass., a corporation of Connecticut

Filed Aug. 18, 1966, Ser. No. 3,513

Term of patent 14 years

(Cl. D74—1)

FIG. 1

FIG. 2

FIG. 3

The broken line illustration of the tape in FIGS. 1, 2 and 4 is for illustrative purposes only.

I claim:

The ornamental design for a tape dispenser, substantially as shown and described.
